UNITED STATES PATENT OFFICE.

HORACE G. BENDER, OF AKRON, OHIO, ASSIGNOR OF ONE-HALF TO LLEWELLYN H. BENDER, OF AKRON, OHIO.

BAG-MAKING MACHINE.

1,240,924.

Specification of Letters Patent. Patented Sept. 25, 1917.

Application filed June 21, 1916. Serial No. 105,059.

To all whom it may concern:

Be it known that I, HORACE G. BENDER, a citizen of the United States, residing at Akron, in the county of Summit and State 5 of Ohio, have invented certain new and useful Improvements in Bag-Making Machines, of which the following is a specification:

The object of the invention is to provide a machine which is adapted to handle a bolt 10 or roll of goods suitable for making salt bags and the like and to convert the goods into bags of standard or other sizes, within limits, the goods or stock in its progress through the machine being first converted into a tube 15 lengthwise and then cut to lengths and sewed transversely and discharged from the machine a complete bag with nothing left to do but to reverse the bag right side out, all substantially as shown and described and 20 particularly pointed out in the claims.

In the accompanying drawings, Figure 1 is a front elevation of the machine, and Fig. 2 is a longitudinal sectional elevation thereof.

Fig. 3 is a rear elevation of the machine and reversed as to Fig. 1. Fig. 4 is a plan view, and Fig. 5 is an end elevation looking in from the right of Fig. 1 or the left of Fig. 3.

Fig. 6 is a cross section on line 6—6, Fig. 4, and Fig. 7 is a cross section on line 7—7, Fig. 4.

Fig. 8 is a more or less diagrammatic plan view of the machine, and Fig. 9 is a sectional elevation of Fig. 8, the said two views serving to illustrate the complete operation and the detail mechanism for which is shown in the other views. Fig. 10, sheet 4, shows a mutilated gear in the table operating 40 mechanism shown in Fig. 7. Fig. 11 is a sectional view showing the main shaft and certain gear connections and other parts operatively connected therewith.

In a general way the machine and its 45 operation can be understood from Figs. 8 and 9. In these views the goods or stock *g* to be converted approaches from the roll over the flat V-shaped folder *f* under pull or tension from the two rolls *r* and is 50 doubled or folded lengthwise as it passes over the point of the said folder into and

through the said rolls. Next to said rolls is the stitching mechanism *m* and needle *n* and which sews the goods lengthwise along its otherwise open edge. Thence the goods 55 passes beneath the counter weight *w* to the tension and feed drum *d* and roller *r'* which are adapted to have an intermittent rotation, as will presently be seen, and for which the slack in the otherwise constant feed through 60 rollers *r* is compensated or taken up by said counterweight. The pause in drum *d* and roller *r'* is momentary as the goods pauses to be severed into uniform and pre-determined lengths by the vertically recip- 65 roating blade or knife *k*.

Having passed the said knife or cutter, which may be of any suitable kind, the bag blank *b* is delivered upon table *t*, which is a member reciprocating transversely of the 70 machine and adapted to deliver the blank to the series of blank feeding disks or rollers 2 and 3 on shafts 2' and 3' respectively, and which rollers have rubber or like surfaces and engage the bag between them and carry 75 the same along while its bottom end is being stitched by the needle *n'*. A fixed table *t'* underlies and supplements the table *t* at its rear and the bottom rolls 3 work through slots in said table, and the said rolls or disks 80 and the needle *n'* are timed to work harmoniously together. This concludes the manufacture and the bag is discharged from the machine.

Now, having this somewhat general view 85 of the operation of the machine as disclosed step by step in Figs. 8 and 9 the more detailed mechanism will be readily understood. Thus, the V-shaped folder for the goods is shown in Fig. 5 as having a flat 90 surface with the point down and set at an inclination vertically and is also slid able horizontally back and forth in suitable guideways in respect to roll *R* by means of a screw rod 4 having a hand lever 4' and 95 which adapts the folder to bring goods of different widths in line at its edge with the stitching needle, which is stationary as to location. The roll *R* is supported on standards 5 laterally adjustable by right and left 100 screws 6 and hand levers 6', adjustment being according to the width of the roll and

each standard moving in corresponding degree relatively to the center line of the goods.

From the said down feed and folding rolls 5 *r* the goods passes, first, to the needle *n* and is stretched longitudinally as described and carried behind the confining rod or roller 8 and beneath the counterweight *w* before passing to and over drum *d*, and which intermediate parts rather serve to take up slack and keep the goods stretched while the said drum and its roller *r'* pauses as the travel is stopped to permit shearing or cutting by knife *k*. This momentary detention 10 of said drum and roller is automatic, and the mechanism comprises a brake shoe 9 for said drum mounted on a pivoted lever 10 having spring pressure 11 behind its outer end and engagement of which is controlled 15 through a suspended pivoted arm 12 which is adapted to be engaged at its free end by a cam like projection 13 on a cam shaft 14. The spring 11 is wound on a stem 15 pivoted on arm 12 and extending through the 20 lever 10, so that the shoe 9 is pressed into engagement by said projection and released by the spring when the arm 12 is free to swing inward.

The said shaft 14 carries a grooved cam 30 16, Fig. 2, which operates the cutter *k* at fixed intervals through a frame comprising the rods 17 having a cross-head 18 with a roller 19 working in said cam, and rotation of drum *d* is timed to occur while said cutter is idle or raised. This timing of the 35 drum is effected through the medium of a vibrating arm 20, Fig. 1, having a segmental rack 21 at its top engaging a pinion 22 on shaft 23 carrying said drum and which arm 40 is operated, Fig. 1, by or from a gear 24 having a coupling rod 25 eccentrically affixed thereto and is engaged with the said arm by an adjustable box bearing 26 therein. The pinion 22 on shaft 23 has a friction 45 clutch or ratchet mechanism 27 in or upon the back thereof and adapted to engage the shaft therewith to effect rotation of the drum on the corresponding swing of arm 20, but also adapted to make an idle play on 50 said shaft during the opposite swing or stroke of said arm and at which time the drum *d* is at rest. The said gear 24 is mounted on a short shaft 28 having bearing in the machine frame and said gear is adapted 55 to be substituted by a larger or smaller wheel according to the length of stroke desired for arm 20 and which is according to the length of bag to be made. Shaft 28 has a gear 29 meshing with pinion 30 on the 60 power shaft *S* to drive the same, see Fig. 11.

The needle *n*, which sews the stock lengthwise, is operated by a line of mechanism through interchangeable gear 24 by pinion 31 mounted on or in a hanging arm *a'*, Figs. 65 1 and 5, and controlled as to locked position

in respect to gear 24 by a hand screw *h* engaged through an ear in the main frame. The gear *g'* engages a pinion *g*² on shaft 32 through which and the line of gears 33, 34, 35, and pinion 36 actuation is imparted to 70 the sewing mechanism for needle *n*, see Fig. 5.

Now, assuming that the goods, stock or material has been folded upon itself lengthwise and sewed along its otherwise open 75 edge by needle *n* and delivered at right angles to its original line of travel through feed drum *d* and roller *r'* to the severing knife or cutter *k*, the bag blank is delivered from said knife upon the reciprocating table 80 *t* and carried forward thereby over the stationary table *t'* and presented to needle *n'* for transverse or end stitching. Here the stitching is regulated according to the width of the bag since the bottom is to be cross-stitched, and table *t* is actuated or reciprocated through mechanism proceeding from shaft 14, Fig. 2, having bevel gear 35 on its end meshing with gear 36, Fig. 7, on a short vertical shaft 37 and on which is mounted 85 a mutilated gear 38. The said gear 38 is segmentally toothed, Fig. 10, or over only about one-third of its periphery and runs idle over the other portion, and meshes with a pinion 39 on a stud shaft 40. An arm 41 95 is fixed on the upper end of this shaft, and a link 42 connects said arm with a sliding box 43, Figs. 2 and 7, which carries a pinion 44 adapted to mesh with a fixed rack 45, Fig. 7, over which it runs and at its top with 100 rack 46 on the base 47 which carries table *t*, see Fig. 7.

The direct effect and value of this organization of parts is to give a quick reciprocating movement to table *t* which delivers 105 the bag to the feed rollers 2 and 3 while the drum is at rest. Thus, assuming that said table is retired to receive a bag blank and arm 41 is on a rotary forward sweep from the dead center shown in Fig. 7 and 110 the gears are in mesh, the pinion 44 will be drawn and rotated forwardly by engagement with fixed rack 45 and this will carry the table *t* forward also on its side guides 48 at the desired speed and until the bag 115 blank is delivered into the bite of said rolls 2 and 3. Then the table *t* will be returned to starting position before gear 38 has exhausted its engagement. The said gear is supposed to have enough teeth to complete 120 the reciprocation of table *t*, which carries a transversely disposed gage and feed plate 50 for the bag blank. This plate is adjustable on its supporting arms 51 according to the width of the bag or blank. The pinion carrying box 43 is adapted to slide over and along the sides of rack 45.

It should have been stated that cam shaft 14 is driven from the main shaft *S* by bevel gear 72 on the end thereof meshing with a 130

gear 73 on countershaft 74 having direct gear connection with the power shaft through gears 75 and 76, Figs. 5 and 11.

Shaft 3 carrying the active rolls 3 is positively rotated by the bevel gears 52, 53, 54 and 55, successively, in mesh as seen at the left in Fig. 2. Gear 55 is carried by shaft 56, which is driven from the shaft 32 by bevel gears 57 and 58, Fig. 2.

10 The needle n' which sews the bottom of the bag is operated by any suitable sewing machine mechanism generally indicated by m' and which is actuated by a line of gears extending back to shaft 56, Fig. 2 and marked 80, 81 and 82. Thus both the stitching or sewing mechanisms are operated together primarily from shaft 32 and their stitching is controlled and made uniform by the interchangeable gear 24, which also controls the intermittent feed of the stock to the cutter. Thus the operation of the feed to the cutter is synchronized with both stitching mechanisms.

The primary rolls r between which the sheet is double folded and drawn down are driven by intermeshing gears 64, Fig. 4, and a gear 65 on the shaft of one of said rolls has driving connection from a vertical shaft 66 having gear 67 at its top in mesh with gear 65. Shaft 66 is driven by gear 68, Fig. 1, meshing with a gear 69 on a driven shaft 70 and which is geared back to shaft 32. As to this line of drive mechanism and other kindred lines it may be suggested that they are not arbitrary nor exclusive, and that the same operating effect can be obtained by equivalent mechanisms and combinations of parts, so that applicant is not to be understood as being restricted to the exact means shown and which the rules require to be somewhat minutely described.

The first direct and important step or operation of the machine consists in the conversion of the plain flat strip or piece 45 of fabric into a practically endless or continuous tube, and the after mechanism has to do with the conversion of the tube into bags of any desirable length. The original stock also may have any width accommodated to the machine, and the operation is continuous and harmonious throughout as described.

Salt bags have been indicated as the object of the machine, but, obviously, neither 55 the use of the bags nor the kind or quality of the fabric is involved in the question of novelty. However, it is to be noted that the machine has to deal with a light limp fabric for salt and sugar and like bags, and which 60 is quite different from a material which has stiffness and can be handled by a different feed and carrying mechanism.

The box bearing 26 in arm 20 for rotating feed roll d is adjustable in said arm by

means of a screw to refine the throw of the 65 arm after other adjustments have been made.

Structurally the machine has a main frame F and a bed B fixed thereon and all the other parts are mounted on said bed and frame.

What I claim is:

1. A machine as described having a support for a fabric roll comprising standards adjustable in respect to each other, a set of tension rolls and a device over which the fabric passes to said rolls provided with 75 means to adjust the same toward and from said roll support.

2. A bag making machine as described comprising means to make a tube from woven fabric, a cutter to sever the tube into 80 bag lengths, and means to feed the tube to the cutter comprising a drum and a roller over the same, a shaft and a cam thereon operatively connected with said cutter and brake mechanism for said drum actuated 85 from said shaft.

3. A bag making machine having means to form a tube from a strip of fabric and a cutter to sever the tube into lengths, feed mechanism for the fabric to said cutter comprising a revolving drum, an oscillating arm 90 operatively engaged with said drum and means to vary the degree of oscillation and thereby vary the feed of stock to said cutter.

4. A machine for sewing bags, comprising sewing mechanism, a device to fold the goods to be sewed, a support for a roll of goods, and means to move said folding device relatively nearer to or farther from said sewing mechanism. 95

5. A machine for sewing bags, comprising a sewing device and a device to fold the goods, one of said devices being movably mounted for adjustment to permit sewing operations on goods of varying width. 105

6. A machine for sewing bags, comprising adjustable supports for a roll of goods, a folding device adjustably related to said supports, and a sewing device for the goods mounted in line with said folding device. 110

7. A machine to make bags from woven fabric, comprising means to carry a roll of the fabric, means to fold the fabric lengthwise and means to stitch the same along one edge, means to sever the tube thus produced 115 into bag blanks, a reciprocating table to receive the blanks and deliver the same at one side of the foregoing mechanism and means to stitch the ends of said blanks.

8. A machine for making finished bags 120 from a length of woven fabric comprising means to fold the fabric lengthwise upon itself and to stitch the folded fabric at its otherwise open edge, a cutter to sever the fabric into bag blanks next succeeding said stitching, sewing mechanism for the bottom end of the bag, a transversely disposed reciprocating table and means thereon to carry 125

- the bag blank from said severing mechanism for the bottom end of the blank, and means to suspend the feed of the blanks at predetermined intervals.
5. 9. A machine as described, having mechanism to fold the bag stock lengthwise upon itself and to stitch the same along its open edge, a cutter to sever the stock into bag blanks and rolls to feed the stock to said cutter, means to momentarily suspend the rotation of said rolls and means to take up slack in the stock while suspension occurs, in combination with stitching mechanism for the end of the blank and a laterally reciprocating table to deliver the blanks thereto.
10. 10. A machine as described having supporting standards for a roll of fabric, a set of tension rolls adapted to exert a downward pull on the fabric and a device between said standards and said tension adapted to contribute to the folding of the fabric lengthwise upon itself, the said device provided with means to adjust the same toward and from the said roll supporting standards according to the width of the fabric.
15. 11. The machine described having a support for a roll of fabric, a set of tension rolls for the fabric and a substantially V-shaped device having a flat face and its point midway over the bite of said rolls and adapted to guide the fabric thereto, the said rolls and said device being at right angles to each other and hand controlled means to adjust said device back and forth in respect to said roll support.
20. 12. A machine as described, comprising a support for a roll of fabric, a set of tension rolls at right angles thereto, a plate of substantially V-shape over which the fabric passes to said rolls, means to adjust the position of said plate in respect to the support for the fabric roll and a fixed stitching mechanism for the fabric next succeeding said tension rolls, whereby the fabric is adjusted to said stitching mechanism.
25. 13. A bag making machine as described comprising means to form a tube from a piece of fabric, a cutter to sever the tube into lengths, feed mechanism for the fabric to the cutter comprising a pair of rolls, a brake for one of said rolls, means to actuate said brake at intervals timed to the action of said cutter and means to take up slack in the fabric while the brake is engaged.
30. 14. A bag making machine as described comprising mechanism adapted to form a tube of woven fabric and a cutter to sever the tube into bag lengths, in combination with a pair of rollers to feed the tube to the cutter and means to rotate said rollers intermittently and to vary the length of tube fed to said cutter according to the length of bag desired.
35. 15. A machine as described having stitching mechanism for the bottom of the bag and means to feed the bag blank thereto, comprising a reciprocating table adapted to carry said blank forward to be stitched and means to operate said table adapted to effect a forward and a return movement thereof in a continuous operation and to rest the table for a predetermined interval after such movement to receive another blank.
40. In testimony whereof I affix my signature in presence of two witnesses:

HORACE G. BENDER.
